(57) **CLAIM**

The ornamental design for a combined foldable desk and USB hub, as shown and described.

DESCRIPTION

FIG. 1 is a perspective view of a design for a combined foldable desk and USB hub, when the desk is completely unfolded, in accordance with the present invention;

FIG. 2 is a zoomed-in view of a portion of the perspective view about the USB hub, in accordance with the present invention;

FIG. 3 is view underneath the perspective view with a tray of the desk moved to a position to enable a view of the bottom of the USB hub, in accordance with the present invention;

FIG. 4 is a zoomed-in view of the view underneath the perspective view, in accordance with the present invention;

FIG. 5 is a back bottom view of the perspective view, in accordance with the present invention;

FIG. 6 is a side view of the perspective view, in accordance with the present invention;

FIG. 7 is a bottom view of the perspective view, when the desk is partially folded (i.e., both legs are folded, but desk portion unfolded), in accordance with the present invention; and,

FIG. 8 is a bottom view of the perspective view, when the desk is completely folded (i.e., both legs and desk portion are folded), in accordance with the present invention.
